UNITED STATES PATENT OFFICE.

LAWRENCE E. JOHNSON, OF WINTHROP, AND EDWARD ERICKSON, OF LYNN, MASSACHUSETTS, ASSIGNORS TO VICTOR SHOE MACHINERY CO., OF BOSTON, MASSACHUSETTS, A CORPORATION OF MASSACHUSETTS.

SHUTTLE FOR SEWING-MACHINES.

1,133,151.

Specification of Letters Patent. Patented Mar. 23, 1915.

Application filed March 28, 1914. Serial No. 828,400.

To all whom it may concern:

Be it known that we, LAWRENCE E. JOHNSON, a citizen of the United States of America, and a resident of Winthrop, in the county of Suffolk and State of Massachusetts, and EDWARD ERICKSON, a subject of the King of Sweden, and a resident of Lynn, in the county of Essex and State of Massachusetts, have invented certain new and useful Improvements in Shuttles for Sewing-Machines, of which the following is a specification.

This invention relates to improvements in shuttles for sewing machines and particularly that class of machines in which the outer soles of shoes are sewed to the welt.

It has for its object the production of a shuttle which will be greatly simplified in construction while its operation will be greatly improved.

The invention consists in certain novel features of construction and arrangement of parts which will be fully understood by reference to the description of the drawings and to the claims hereinafter given.

Of the drawings: Figure 1 represents a section through the shuttle and the driving mechanism therefor. Fig. 2 represents an elevation of one face of the shuttle. Fig. 3 represents an elevation of the opposite face thereof. Fig. 4 represents an edge view of said shuttle. Fig. 5 represents a section through the shuttle. Fig. 6 represents a sectional detail of the shuttle, the cutting plane being on line 6-6 on Fig. 3. Fig. 7 represents a sectional detail of the shuttle, the cutting plane being on line 7-7 on Fig. 3, and Fig. 8 represents an elevation of a portion of the driving member showing the shuttle coating lug.

In the drawings, 10 is the shell of the shuttle substantially circular with a portion of its periphery cut away as at 11 to form a depression adapted to receive the projecting lug 12 of the driving member 13.

The driving member 13 is provided with an axially disposed cylindrical shank 14 mounted in a bearing 15 in the frame 16 of a sewing machine and its opposite end 50 has secured thereto a pinion 17 the teeth of which mesh with the teeth of a segment 18 on the end of a lever 19 to which an oscillatory movement is imparted at predeter-

mined times during the operation of the machine, thereby causing the shuttle case 55 or shell 10 to be oscillated. The peripheral wall of said shuttle case 10 is provided with a projecting bead or flange 20 disposed in a groove 21 in the frame of the machine, this groove 21 forming a raceway for the 60 shuttle case and the bead 20 disposed therein preventing any lateral displacement of said shuttle.

The driving mechanism herein shown and described forms no part of the present invention and is only illustrated for convenience in describing the operation of the shuttle. The inner face of said shuttle case 10, viz., that face adjacent to the driving member 13, is provided with an annular recess 65 22, the axis of which is parallel with and eccentric to the axis of the said shuttle case.

In the annular recess 22 is positioned the bobbin or spool 23 carrying the shuttle thread which passes from said bobbin 23 through a 70 radial passage 24 in the peripheral wall of the shuttle case. As the thread passes through the opening 24 a friction is created thereon by the spring pressed ball 25 which prevents the thread paying out with too 75 much freedom. The thread extends from the opening 24 to an opening 26 in the shell 10 of the shuttle, said thread passing along a groove 27 in the face of the shell so that it is protected from any chafing thereon during the oscillation of the shuttle. From the opening 26 the thread passes through an eye 80 28 in a member 29 pivoted at 30 to the shell 10. This pivoted member 29 is adapted to retain the bobbin or spool 23 in its recess 85 and may be moved in the direction of the arrow *a* on Fig. 3 by depressing the locking pin 31, thereby permitting the removal or insertion of the bobbin 23. The member 29 not only positions the bobbin but being 90 of yielding material creates sufficient friction on the bobbin to prevent it from spinning.

The locking pin 31 is mounted in a chamber in the shuttle shell and its outward extension engages with a notch in the edge of the member 29. The chamber 32 is closed by the threaded cap 33 and in the chamber is a spring 34 forcing the pin 31 outwardly.

The ball 25 is positioned in an elongated 105 chamber 35 perpendicular to the passage

24 and closed by a threaded plug 36 between which and the ball 25 is interposed a helical spring 37 the tension of which may be regulated by the adjustment of said plug 36. 5 The rounded face of the ball 25 bears on the thread as it passes from the bobbin and creates a friction thereon, but owing to its smooth rounded surface no injury to the thread can occur. The ball 25 is free to 10 revolve in its seat in the end of the spring 37.

The opening 26 extending through the shuttle case 10 from face to face is centrally disposed in the hub 38 on which the bobbin 23 is mounted and about the axis of 15 which it is free to turn.

The shuttle case 10 is provided with a loop engaging point 39 extending beyond the outer face thereof and having a laterally oblique surface. By this construction 20 the point is always sure to enter the loop of thread when spread to receive said point.

It is believed that the operation and many advantages of the invention will be fully understood from the foregoing description.

25 Having thus described our invention, we claim:

1. A shuttle case containing a bobbin and having a radial passage in said case through which the thread from said bobbin is fed, 30 and an elongated chamber perpendicular to said passage and parallel to the axis of said bobbin, and a spring pressed friction member in said chamber adapted to press on said thread against the outer wall of said passage 35 as it passes therethrough.

2. A shuttle case containing a bobbin and having a radial passage in said case through which the thread from said bobbin is fed, and a spring pressed revolvable ball adapted 40 to press on said thread as it passes through said passage.

3. A shuttle case provided with an annular recess in one face and having a radial passage in the peripheral wall communicating with said recess and an elongated cham- 45

ber perpendicular to and communicating with said passage; a bobbin in said recess carrying thread adapted to pass therefrom through said peripheral passage; and a revolvable spring pressed friction member in 50 said chamber adapted to press said thread against the outer wall of said passage as it passes therethrough.

4. A shuttle case provided with an annular recess in one face and having a radial 55 passage in the peripheral wall communicating with said recess; a bobbin in said recess, carrying thread adapted to pass therefrom through said passage; and a revolvable member adapted to press on said thread as it 60 passes through said passage.

5. A shuttle case provided with an annular recess in one face; a bobbin therein; a bobbin retaining member pivoted to said case and provided with a notch in one edge; 65 and a spring pressed locking device coacting with the said notch normally adapted to prevent movement of said retaining member about its pivot.

6. A shuttle case having a bobbin containing recess in one face thereof and provided with a central cylindrical bearing hub for said bobbin, said hub having a centrally disposed hole extending through its entire 70 length for the passage of the thread from said bobbin; a bobbin retaining member pivotally secured to the inner face of the shuttle having a perforation therein opposite the hole in said hub and through which the bobbin thread is adapted to pass and provided with a notch in one edge; and yielding means coacting with said notch for positioning said retaining member. 75

Signed by us at Boston, Mass., this 26th day of March, 1914.
